REPEATING FUSE

Tomlinson Fort Johnson, Atlanta, Ga.

Application March 4, 1935, Serial No. 9,340

16 Claims. (Cl. 200—126)

This invention relates to repeating fuses or automatic fuse-reclosers for high tension electric circuits and, among other objects, aims to provide improved and greatly simplified mechanism having means to replace a series of fuses successively after they are blown due to an overload which generally results from some transient condition, such as a lightning flash-over or a temporary short circuit. Another aim of the invention is to provide simple mechanism whereby blown fuse elements may be quickly replaced and again put in service. Also a feature of the invention is the provision of adjustable time-delay mechanism whereby the reclosing fuse will serve as a delayed action switch having all of the advantages of the more expensive reclosing oil circuit-breakers.

This application is a continuation-in-part of my copending application, Ser. No. 662,143 filed March 22, 1933.

Other aims and advantages of the invention will appear in the specification, when considered in connection with the accompanying drawings, wherein:

Fig. 1 is a side elevation of a reclosing fuse assembly embodying the invention;

Fig. 2 is a front elevation of the fuse mechanism shown in Fig. 1;

Fig. 3 is a lower end view or bottom plan of the mechanism;

Figs. 4, 5 and 6 are sectional views taken on the lines 4—4, 5—5 and 6—6, respectively, of Fig. 2;

Figs. 7, 8, 9 and 10 are elevations of latch members for the fuse sockets;

Fig. 11 is a sectional view partly in elevation of the preferred form of fuse sockets;

Fig. 12 is a central sectional view of one of the fuse units mounted in its socket;

Fig. 13 is a side elevation of one of the fuse units ready to be inserted in one of the sockets;

Fig. 14 is a lower end view of the unit shown in Fig. 13;

Fig. 15 is a fragmentary elevation showing the position of the parts after a fuse is blown;

Fig. 16 is a fragmentary sectional view taken on the line 16—16 of Fig. 2;

Fig. 17 is a similar sectional view showing the fuse unit in its circuit-closing position;

Fig. 18 is a central sectional view of a dashpot on an enlarged scale;

Fig. 19 is a sectional view taken on the line 19—19 of Fig. 18; and

Fig. 20 is a view similar to Fig. 3 but showing

two of the fuse units having time delay mechanism applied thereto.

Referring particularly to the drawings, the reclosing fuse mechanism is shown as being mounted on insulators 10 and 11 which are secured to a suitable vertical support 12 (Fig. 2), which is usually in the form of a structural channel member. The automatic mechanism is carried by a metal bracket 13 bolted to the insulator 10 and expulsion units 14, 15 and 16 are pivotally mounted on this bracket so as to be swung successively into circuit-closing positions, engaging jaws 17 mounted on a bracket 18 which is bolted to the other insulator 11. The brackets 13 and 18 are made of bronze or other suitable 10 conducting metal and each has a terminal arm 19 adapted to be connected to one of the phases of a transmission line.

Referring to Figs. 1, 2 and 3, the bracket 13 is shown as having four upstanding gears 20, 21, 20 22 and 23 between adjacent pairs of which three cylindrical open ended metal sockets 24 are pivotally mounted to receive the respective fuse units 14, 15 and 16. It is to be understood that any number of fuse units may be employed. In this 25 instance, each of the sockets has a pair of integrally opposed trunnions 25 and aligned holes are drilled through these trunnions to receive hinge pins 26 forced into openings in the two intermediate ears 21 and 22 and short pins 27 flush 30 with the outer faces of the outside ears 20 and 23. The arrangement is such that the sockets are mounted for independent swinging movement. Furthermore, the sockets can be assembled in succession between the brackets, and each 35 of the sockets has a flared end within which a metal ferrule 28 on each of the fuse units is guided endwise. Metal ferrules 29 are also secured to the free ends of the tubes which are made of insulating material to contact with the 40 jaws 17.

The ferrules 28 are shown as having surface contact with the sockets. In Figs. 11 and 12, the sockets have openings at one side to receive spring tongues 30 projecting into the sockets and 45 making good electrical contact with the lower portions of the ferrules when they are pushed home. Furthermore, the sockets are electrically connected to the base of the bracket 13 by means of flexible conductors or cables 31 conveniently 50 secured to the sockets by screws 32 used to secure the tongues 30.

In this example, the fuse units are normally biased toward their closed positions by means of tension springs 33 (Figs. 1, 3, 16 and 17), each 55

connected at one end to a notched arm 34 integral with the upper end of one of the sockets and, at its other end, to an adjustable pivoted arm 35. The arms 35 are journaled on shafts 36, 37 and 38 which are in turn journaled in the ears 20 to 23 inclusive and another set of short ears 39, 40 and 41 best shown in Figs. 2 and 3. The arrangement is such that the fuse units can be tensioned in cocked position at an angle of about 45° to the vertical and they are adapted to be latched or locked in this position by means of latch arms 42 secured to the respective shafts 36 to 38 inclusive adjacent to the arms 35 and each carrying a roller 43 adapted to engage integral brackets 44 on the fuse sockets shown as extending at approximately right angles to their axes. The brackets 44 are flanged at their free ends and have screws 45 to act as adjustable stops for the rollers 43 when the latch arms are swung into their cocked positions, as shown in Fig. 16.

The latch arms 42 and the spring arms 35 are mounted side by side on each of their shafts and the spring arms are adapted to be adjusted relative to the latch arms so as to displace the spring connections from alignment with the shaft and transmit movement to the latches. Also, the arms may be adjusted to vary the tension of the springs. For this purpose, each arm 35 has an ear carrying a set screw 46 engaging a lateral ear 47 on the latch arm 42. Also, each spring arm is adjustably secured to its latch arm by a machine screw 48 in the latch arm passing through an elongated slot in a lateral ear on the spring arm 49. The position of the arms and connections are such that the act of swinging each fuse unit to its cocked position causes the springs to impart full cocking movement to the latch arms so that they are locked automatically. In the cocked position the latch arms act as the stiff legs which are approximately parallel with the sockets and normal to the faces of the brackets 44. Incidentally, the sockets are shown as being limited in their swinging movement to cocked position by means of lateral lugs 50 on the respective sockets adapted to engage the upper edges of the adjacent brackets.

The mechanism is designed to trip the fuses automatically in sequence or in succession when the fuse elements are blown. For this purpose, the latch members are adapted to be tripped by means of triggers which are operated incident to the blowing of the fuses. Referring to Figs. 1, 2, and 3, the first fuse unit 14 is adapted to be released or tripped by means of a manually operated trip arm 51 mounted on the first latch shaft 36 outside of the bracket 20. This fuse unit is shown in its circuit closing or active position. On the second latch shaft 37 there is shown a trigger 52 having an offset portion or finger in line with the open end of the first fuse socket. The arrangement is such that when the trigger 52 is moved downwardly, it trips the second fuse latch. Likewise, there is a second trigger 52, identical with the first one, on the third latch shaft 38 and it is arranged to be tripped when the second fuse unit is blown so as to release the third fuse unit. A third trigger 52 is shown as being mounted adjacent to the third fuse and fixed on a fourth trigger shaft 53 which projects through and beyond the outside bracket 23. This shaft carries an arm 54 and the opposite shaft 36 carries a similar arm 55 to the outer ends of which a bar 56 is connected. The arrangement is such that when the third

fuse unit 16 is blown, the two arms and the bar will trip the latch for the first fuse, in the event that it was left in cocked position. By this arrangement, any blown fuses may be replaced, while any good one is connected and they will be tripped in continuous sequence.

Referring now to the automatic mechanism for tripping the triggers, the fuse units are arranged to expel their ruptured fuse elements through the rear or lower open ends of the fuse 10 sockets and thereby effect the release of the triggers. Referring to Fig. 12, the fuse tubes each carry a tension fuse wire 57 having a fusible link soldered at its upper end to a member 58. These fuses are of a well known type. The upper ends of the fuse tubes are open and the ferrules 29 extend beyond them. Metal disks 59 are inserted in the open ends of the ferrules against the ends of the tubes and carry the usual flanged washers or adapters 60 providing contact members for rounded heads 61 on the upper ends of the fuse members 58. The ends of the ferrules are shown as being screw-threaded and closed by plugs 62 of good conducting material adapted to be tightly screwed against the heads 61 and make good electrical contact therewith. Thus, the fuse links are easily removable and replaceable, the ends of the plugs having screw driver slots for that purpose.

The fuse wires 57 project through the lower open ends of the lower ferrules 28 and are adapted to be connected to spring tensioned members which, when released, strike the triggers. In this example, bracket members 63 are shown as being clamped on the ferrules 28 near their upper ends and project at an angle to the axes of the tubes. The outer free ends of the bracket members have spaced hinge ears 64 to which are connected knee-jointed hammers 40 each comprising an arm 65 secured on a pin 66 projecting through the hinge ears 64 and a hammer member 67 pivotally connected between ears 68 on the arm 65 and presenting a cam gripping surface 69 cooperating with a gripping face 70 between the ears 68. The hammer members are shown as being notched or bifurcated at 71 to receive the fuse wires which are threaded through the notches and between the cam surface 69 and the gripping surface 70, the hammer having a smooth central guiding groove to prevent displacement of and sharp bends in the wire. Also, the end of each hammer member has a bulb-shaped enlargement 72 adapted to guide it into the open end of the ferrule 28.

Mounted on the hinge pin 66 is a coil spring 73 normally urging the hammer to swing downwardly so as to engage a trigger and knock it to its latch releasing position. To make good electrical contact between the bracket arms and the hammer members, flexible wires 74 are shown as connecting them. Furthermore, the spring-urged arm 65 of the hammer is limited in its swinging movement by means of a pair of stop shoulders 75 machine adjacent to the ears 64 to engage the outer edges of the ears when the hammer is swung through approximately 180° as best shown in Fig. 15. Moreover, the swinging movement of the hammer member 67 with respect to the arm 70 or leg 65 is limited by means of a pair of lateral stop pins 76 adapted to engage the edges of the ears 68. The arrangement is such that when the hammer arms are swung into a position so that the forked ends of the hammers close the lower

ends of the ferrules and the two arms are swung upwardly at their joint from the position shown in Figs. 12 and 13, the free end of the fuse wires may be inserted between the gripping faces 69 and 70. Then, when the arms are released the spring tension will cause them to swing into the position shown in Figs. 12 and 13, not only to grip and hold the end of the fuse wire but also to place it under a slight tension. The tension 10 on the wire is determined by the strength of the coil spring 73 and the length of the knee-jointed hammer.

As soon as a fuse link blows, the hammer is released and strikes the trigger finger below it. 15 Then, it swings to the fuse blown position shown in Fig. 15. The power of the trigger hammers is somewhat augmented by gravity and by an explosion within the fuse tube causing the gas formed to escape through the open end of the 20 tube. Hence, the springs do not need to be of very great strength to insure positive action. Due to the swinging action of the hammer, the knee-joint is broken and the blown fuse wire is released from its gripping engagement so that it is 25 thrown outwardly and downwardly to the ground. Furthermore, a lineman can instantly determine which fuses have been blown by the positions of the hammers as shown in Fig. 15.

Referring to Figs. 3, 6, 11 and 12, each of the 30 fuse sockets is shown as having a longitudinal slot 71 in its front wall and the hammer arms 67 present narrow neck portions 78 insertable in said slots to permit the units to be pushed home in the sockets. Also, the brackets 63 have 35 tensions 79 presenting rounded lower edges adapted to engage and fit snugly into the upper end portions of the slots so as to prevent rotation of the fuse units and keep the hammers in line with their respective triggers. Moreover, the 40 clamping members of the brackets serve as stops to limit the endwise movement of the fuse tubes when they are inserted in the sockets. The reduced neck portions 78 on the hammers are somewhat narrower than the width of the slots 71 45 in the sockets so that when the fuse tubes are centered in the sockets by the bracket projections 79, the hammers are free to swing downwardly without binding in the slots at the lower ends of the sockets.

To enable fuse replacers of this type to serve the 50 same purpose as reclosing oil circuit breakers, it is necessary to delay the reclosing operation of one or more of the fuse units after a fuse is blown. In Figs. 1, 2 and 3, the fuse assembly is shown as being provided with one time-delayed fuse unit. 55 In this instance, the third fuse unit 16 is connected to a dashpot having a cylinder 80 pivotally connected by trunnions 81 to bracket 82 which is bolted to the outside of the ear 23 and 60 has a piston rod 83 adjustably connected to a lateral arm or pin 84 on the upper end portion of the third socket by means of an extension 85 having an elongated slot 86 engaging the pin. The dashpot, which is shown in detail in Figs. 65 18 and 19, is of the leakage and by-pass type preferably being filled with oil and having a cup-shaped piston 87 presenting openings 88 closed by a check valve 89 limited in its opening movement by a pin 90. The cylinder 80 is filled 70 with oil through filling plugs 91 aligned with by-pass openings 92 and 93 which communicate with a by-pass 94. The upper end of the dashpot cylinder is shown as being closed by a head 95 which is preferably secured in the end of the 75 cylinder by brazing or welding. This head car-

ries a stuffing box 96 through which the piston rod extends and the packing is adapted to be compressed by a packing gland 97. The upper end of the piston rod is screw threaded into the extension 85 and secured by means of a lock 5 nut 98. A compression spring 99 surrounds the piston rod between the packing gland and the lock nut normally to urge the piston upwardly and keep the innermost end of the slot 86 in the extension in engagement with the pin 84. The construction and arrangement are such that the piston is automatically moved to the cocked position or the position shown in Fig. 18 when the third fuse unit is swung to its cocked position.

The piston serves to delay the release of the 15 fuse unit due to the trapped oil in the outer or lower end of the cylinder below the cup-shaped piston. After the latch for the third fuse is released and the unit is ready to close, the pin 84 moves freely in the slot 86 until it contacts the 20 outer end and imparts a jerk to the piston. This free initial movement of the fuse unit and socket prevents the tripped latch 42 from returning to its stiff-leg or locking position which otherwise would prevent the fuse from closing. The bracket faces 25 are slightly offset (Fig. 16) to provide ample clearance for the rollers 43 when they are tripped. However, oil must leak slowly past the piston with the check valve closed until the lower end of the piston uncovers the by-pass port 93. As soon 30 as this happens, oil by-passes very rapidly through the ports 92 and 93 around the piston and permits rapid closing of the fuse unit. The quick movement is necessary to prevent the switches from being burned off as they approach the jaws. 35 Now, the time delay can be adjusted by varying the distance which the piston 87 overlaps the lowermost edge of the port 93. This is done by the screw-threaded connection between the extension 85 and the piston rod 83. By extending 40 the effective length of the piston rod from the cocked position of the pin 84, it may be so adjusted that the piston will be positioned at the extreme bottom end of the cylinder. This will give a maximum time delay. On the contrary, the 45 effective length of the piston rod may be shortened to reduce the amount of overlap of the piston or to change its position so that it just covers the port 93 and thereby reduces the time delay to a minimum. Incidentally, when the piston is 50 adjusted as shown, the compression spring 99 supports its weight and prevents it from falling in the cylinder to a different time delaying position from the position for which it is adjusted. In practice, it is desirable to vary the time delay from 55 approximately a half second to 2 minutes.

When only one dashpot is used on the third fuse unit as shown, it is desirable that this fuse unit shall always be the last one to close. Without a dashpot, the sequence of operation is immaterial 60 because any two units may be left cocked and the other unit in its circuit closing position. With the dashpot, the first fuse unit is always left closed as shown in Figs. 2 and 3. When the first fuse unit blows, the middle one will be tripped and try 65 to restore the service practically instantaneously. If the middle unit fails to restore the service and is blown due to a continued abnormal condition, the third fuse will be tripped and delayed in its closing for a predetermined time intended to permit any ordinary transient condition to clear up.

The blown fuse units are adapted to be manually opened by using ordinary switch hooks engaged in hook eyes 100 conveniently clamped on the lower portions of the upper ferrules 29 as best 71

shown in Fig. 1. These hook eyes slightly increase the momentum of the fuse units when they are forcibly closed by the tension springs 33. Hence, the switch jaws are provided with combined spring shock absorbers and contact members 101. These springs are conveniently made of phosphor bronze strips bent U-shaped with their free ends projecting toward the hinged ends of the fuse units. As shown in Figs. 4 and 5, the 10 jaws have relatively movable jaw elements 102 on spring brackets 103 so that they automatically adjust themselves to contact with the sides of the fuse ferrules 29 and the spring pressure of the jaws may be varied by means of bolts 104 passing 15 through the spring brackets. These incidental features insure good electrical contact between the fuse units and the jaws.

It will be understood that the fuse elements may easily be replaced by bodily removing each blown 20 fuse unit from its fuse socket with an ordinary switch hook and taking it down to a platform or to the ground. A lineman may substitute new units for ones having blown fuses and take the old ones to a shop for inspection and replacement 25 of the fuse elements. The units are interchangeable because they are identical and they may be inserted in the sockets also by using the switch hook so that a lineman does not need to come in physical contact even with the blown 30 assembled units.

It is sometimes desirable to use two time-delayed fuses in a reclosing device of this character. This is especially true if the line is subjected to more or less frequent lightning flashovers or if the inspections are infrequent. Obviously, two time delayed closures will insure two restorations of service if the abnormal conditions do not persist too long. In the embodiment of 35 the invention shown in Fig. 20, two dashpots are shown as being provided for the two outside fuse units. These two units are selected because it is most convenient to mount the dashpots adjacent to them. A dashpot is not necessary for the fuse which is left in its active position. In this case, 40 the middle fuse is placed in service and the two outside fuses are left cocked. Herein lies one of the advantages of the continuous sequential operation of the fuse units. The same mechanism is employed for operating fuses either with or without dashpots and this enables it to be 45 standardized. It will be understood that when the middle fuse unit shown in Fig. 20 blows, the right hand fuse unit will be tripped and, when the right hand fuse unit blows, the left hand unit 50 will be tripped by means of the arms 55 and cross bar 56. In this case, the two right hand triggers 55 are the active ones, the left hand trigger having been swung to its tripped position to release the middle fuse and put it in service. In all other respects, the construction and operation of the 55 mechanism shown in Fig. 20 is identical with that hereinbefore described. This type of mechanism is best suited for displacing the far more expensive automatic, reclosing oil circuit breakers.

60 From the foregoing description, it will be seen that the mechanism is relatively simple in its construction and design. It is very rugged and has no delicate mechanical parts which require quick replacement or expensive maintenance. Inspection and replacement of the fuse elements 65 may be made by ordinary linemen and there is no possibility of making a mistake as to the fuse units which have been blown. Service tests have shown that the fuse replacers are absolutely 70 dependable in operation. In fact, they have been 75

adopted as standard equipment on some high tension electrical systems.

Obviously, the present invention is not restricted to the particular embodiment thereof herein shown and described. Moreover, it is not 8 indispensable that all the features of the invention be used conjointly, since they may be employed advantageously in various combinations and sub-combinations.

What is claimed is:

10 1. In a fuse replacer of the character described, a plurality of pivoted expulsion fuse units each arranged to expel its fuse elements through its pivoted end; means normally biasing said fuse units to their circuit closing position; means to latch the inactive fuses in cocked position ready to be closed as the active fuses are blown in succession; triggers connected to operate each of said latch means in the order of succession; and spring urged pivoted striker 15 members for said triggers assembled on the fuse units and connected to be released by the fuses when they are blown.

2. An automatic fuse changer for electric circuits comprising, in combination, a plurality of 25 expulsion fuse units; open ended cylindrical sockets each pivoted at one end carrying said fuse units; tension springs connected to the free ends of said sockets normally to swing said fuse units to circuit closing position; latch means to 30 hold said sockets in cocked position; and triggers connected to the respective latches lying immediately behind the rear open ends of adjacent fuse sockets when in closed position and each adapted to be tripped by the next adjacent fuse. 35

3. In a repeating fuse of the character described, a pair of spaced insulators; a bracket mounted on one of said insulators having a plurality of spaced ears at right angles thereto; a plurality of substantially cylindrical fuse sockets 40 each having a flared end and pivotally mounted at its opposite end between pairs of said ears; expulsion fuses having their contact sleeves removably inserted in the flared ends of said sockets and adapted to project the expelled elements through the rear ends of said sockets; tension springs connected to the flared ends of said sockets and normally urging them to circuit closing position; latch mechanism connected to hold said sockets in cocked position; fuse-operated tripping mechanism for the latches of successive fuses arranged to release the latch of each succeeding adjacent fuse as the fuses are blown and their fuse elements are expelled through the rear ends of said sockets; and a 55 bracket on the other insulator carrying contact clips to receive the contact ends of the respective fuse units.

4. In an automatic fuse replacing mechanism of the class described, a pair of spaced insulators; a bracket mounted on one of said insulators and having a plurality of integral ears at right angles thereto; a plurality of open substantially cylindrical fuse sockets each pivotally mounted adjacent to one end on said ears and having 60 springs connected to their free ends normally to urge them to circuit closing position; a plurality of expulsion fuse units mounted in said sockets and having tensioned fuse elements arranged to discharge through the rear ends of said sockets; 65 latch and trip mechanism mounted on said bracket connected to hold the successive fuses in cocked position and adapted to be operated by the blown fuses to release the fuse sockets in succession; and a bracket carrying adjacent jaws 70 75

on the other of said insulators cooperating with each of said fuse units.

5. In a fuse replacer of the character described, a bracket carrying a plurality of pivoted cylindrical sockets having flared mouths; a plurality of expulsion fuse units removably mounted in said sockets and adapted to project the fuse elements through the rear ends of said sockets; a second bracket carrying a plurality of jaws for said fuse units; tension coil springs normally urging said fuse units to their circuit closing position and connected to said sockets; a separate rotatable shaft adjacent to each of said sockets carrying a locking latch and an offset trigger, said offset trigger being positioned directly behind an adjacent socket to be operated by the fuse therein as it is blown; and an arm on each of said shafts also connected to one of said springs and arranged to restore the latch and the trigger automatically to their cocked position when the corresponding fuse unit is swung to its circuit opening position.

6. In an automatic fuse replacer of the character described, a bracket having a conductor terminal; a plurality of spaced parallel ears on the bracket; a plurality of cylindrical open ended sockets each having hollow lateral trunnions adjacent to one end inserted in the respective spaces between the ears; pivot pins pressed into the ears through the trunnions; tension springs connected to the free ends of the sockets normally biasing them to swing to their circuit closing positions; expulsion fuse elements each inserted at one end into said sockets; separate shafts journaled on said bracket, one for each fuse unit; a latch arm on each shaft to engage a socket and hold it in cocked position; triggers also fixed on each of said shafts adapted to trip the latch for an adjacent fuse unit, one trigger being manually operable to trip the first fuse unit and the other triggers being operable automatically as the preceding fuse units are blown whereby the fuses are closed in succession; and a bracket carrying contact clips for the respective fuses.

7. In a fuse replacer of the character described, a bracket carrying a plurality of pivoted cylindrical sockets each having a flared mouth; a plurality of expulsion fuse units removably inserted through the flared mouths of said sockets and adapted to project the fuse elements through the rear ends of said sockets; a second bracket carrying a plurality of adjacent contact jaws for said fuse units; springs normally urging said fuse units to their circuit closing position and connected to said sockets; a separate shaft adjacent to each of said sockets carrying a locking latch and an offset trigger, said offset trigger being arranged directly behind the rear end of an adjacent socket to be operated by the fuse therein as it is blown; and an arm on each of said shafts also connected to one of said springs and arranged automatically to restore the latch and the trigger to their cocked position when the corresponding fuse is moved to its circuit opening position.

8. In a fuse replacer of the character described, a metal bracket; a plurality of open ended, cylindrical sockets each pivoted at one end to said bracket; fuse units removably and interchangeably mounted in said sockets; a plurality of jaws for said fuse units; means normally biasing said sockets to swing said fuse units to their circuit closing positions; latch means for holding said sockets in cocked position with the

fuse units out of contact with their respective jaws, including arms carrying rollers and brackets on said sockets with which said rollers are adapted to contact; offset trigger members operatively connected to said latch members and arranged to be tripped in succession as adjacent fuse units are blown; and hammer members associated with each of said fuse units adapted to strike said trigger members.

9. In a fuse replacer of the character described, a bracket having a plurality of spaced ears thereon; three adjacent cylindrical sockets open at both ends and pivotally mounted at one end between pairs of said ears; a tubular fuse unit removably mounted in each of said sockets; a plurality of adjacent jaws for the fuse units; means normally biasing said sockets to swing the fuse units to their circuit closing position; latches cooperating with said sockets to hold them in cocked position with the fuses out of contact with said jaws; triggers operatively connected to the latches and arranged to be actuated by adjacent fuse units when they are blown to trip the latches in succession beginning with any fuse unit of the group which may be initially closed, the trigger of the third fuse socket being operatively connected to the latch for the first fuse socket; and spring tensioned striker members for said triggers mounted on said fuse units each secured to a fuse element and supported to swing outwardly against the respective triggers to trip them and eject the fuse elements.

10. In a fuse replacer of the character described, a metal bracket; a plurality of adjacent sockets pivotally mounted on the bracket; elongated fuse units removably mounted in said sockets; a bracket having a plurality of adjacent jaws for said fuse units; means normally biasing said sockets to swing the fuse units to their circuit closing position; latch and trip means associated with said sockets automatically to lock them in open position as they are swung on their pivots and adapted to be operated in succession as the fuse units are blown; and spring tensioned striker members associated with each of said fuse units and adapted to be released when the fuse element is blown and thereby trip the latch means for an adjacent socket whereby the fuse units are tripped in succession.

11. In an automatic fuse replacer of the character described, a bracket; a plurality of open ended cylindrical sockets pivotally mounted adjacent to one end on said bracket and each having an elongated slot throughout its length; expulsion fuse units mounted in said sockets; jaws for said fuse units; means normally biasing said fuse units to circuit closing position; latch and trip means associated with said sockets adapted to lock them in open position as they are swung on their pivots; trigger members associated with said latches and arranged to be operated in succession as the fuse units are blown; angle brackets on each of said fuse units having means to limit the movement of the fuse units in said sockets; and jointed, spring tensioned hammer members pivotally mounted on said angle brackets each having an associated clamp and said fuse units having fuse elements projecting through said sockets and secured in said clamps with the fuse element tensioned, said hammer members having striker elements arranged behind each of said sockets and presenting narrow neck portions adapted to guide the units into their proper positions through said slots whereby the hammer

members are positioned to strike the respective trip members for the latches.

12. In an automatic fuse replacer of the character described, a plurality of pivotally mounted fuse units each normally biased to swing toward its circuit closing position; latch and trip means associated with said fuse units connected to be operated in succession as the fuse units are blown; and a dashpot connected to at least one of said fuse units to delay the closing movement thereof.

13. In an automatic fuse replacer of the character described, a plurality of pivotally mounted fuse units each normally biased to swing toward its circuit closing position; latch and trip means associated with said fuse units connected to be operated in succession as the fuse units are blown; and adjustable time delay means for one of said fuse units including a pivotally mounted dashpot having a piston connected to retard the closing movement of the fuse unit.

14. In a fuse replacer of the character described, a bracket; three fuse sockets pivotally mounted on the bracket; elongated fuse units mounted in said sockets; jaws for said fuse units; springs normally biasing said sockets to swing the fuse units to circuit closing position; latch and trip means arranged to hold the sockets in cocked position with the fuse units swung out of their cir-

cuit closing positions; spring tensioned striker members for said trip means associated with each of said fuse units and adapted to trip the latches of the fuse sockets in succession; a dashpot of the leakage and by-pass type associated with one of said fuse sockets having an adjustable piston rod to vary the time delay in closing the connected fuse unit.

15. In a fuse replacer of the character described, an active fuse unit; a spring biased fuse unit; means to latch the spring biased fuse unit in its open position; trip means for said biased fuse unit adapted to be actuated to release said unit when the active fuse unit is blown; fluid controlled time delay means removably connected to the biased fuse unit; and means whereby the time delay may be varied.

16. In a fuse replacer of the character described, an active fuse unit; a spring biased fuse unit; means to latch the spring biased fuse unit in its open position; trip means for said biased fuse unit adapted to be actuated to release said unit when the active fuse unit is blown; a dashpot of the leakage and by-pass type having a piston connected to said biased fuse unit; and means to adjust the position of the piston to vary the time delay in closing said fuse unit.

TOMLINSON FORT JOHNSON.
